UNITED STATES PATENT OFFICE.

STEPHEN H. LOVETT, OF MILES CITY, MONTANA.

CAR-DOOR.

1,378,475.

Specification of Letters Patent. Patented May 17, 1921.

Application filed September 4, 1919. Serial No. 321,521.

To all whom it may concern:

Be it known that I, STEPHEN H. LOVETT, a citizen of the United States, residing at Miles City, in the county of Custer and State 5 of Montana, have invented certain new and useful Improvements in Car-Doors, of which the following is a specification.

The invention has relation to closures for box cars in which a commodity is hauled in 10 bulk and specifically considered, the invention relates to freight car doors of the type which are mounted to open and close by a tilting or rocking movement.

The invention relates more particularly to 15 the means for sustaining the wear and for preventing displacement of the door and holding the same in proper position in either open or closed position or at any intermediate position.

20 The drawings illustrate a preferred embodiment of the invention. However, it is to be understood that in adapting the same to meet different conditions, various changes in the form, proportion, and minor details 25 of construction may be resorted to without departing from the nature of the invention as claimed hereinafter.

By referring to the accompanying drawings,

30 Figure 1 illustrates a portion of a freight car provided with a tilting door embodying the invention, the full lines showing the door closed and the dotted lines illustrating the position of the door when open.

35 Fig. 2 is a horizontal section on the line 2—2 of Fig. 1.

Fig. 3 is a vertical section on the line 3—3 of Fig. 1.

40 Corresponding and like parts are referred to in the following description and indicated in the several views of the drawings by like reference characters.

45 The numeral 1 designates the side of a freight car in which is provided the usual opening adapted to be closed in the present instance by means of a door 2 which is mounted to open and close by a tilting or rocking movement. The door is maintained in proper position by means of brackets 3 and 4, the brackets 3 being disposed at one side of the door to engage an edge portion thereof and the bracket 4 being located below the door opening so as to engage the lower portion of the door. The brackets 50 55 are adjustable by means of hand nuts

which are mounted upon threaded stems projecting outwardly from the side of the car. The brackets are offset and the ends adapted to engage the door and possess a certain degree of resiliency so as to press 60 the door close against the side of the car and thereby prevent any play and obviate resulting rattle. The door when closed may be secured by any suitable means and as shown in Figs. 1 and 3, a strap 6 is loosely connected to the upper beam of the car and is adapted to engage a stem 7 projecting from the door, the projecting end of the stem receiving a hand nut 8 by means of which the door may be drawn close against the side of 70 the car.

When the door is in open position, it is retained in place by means of a vertical strip 9 and a horizontal strip 10. A strip 11 is spaced from a side of the car a distance 75 to admit of the door 2 passing between the strip and the outer side of the car body. The strip 11 acts in the capacity of a keeper to prevent outward displacement of the door.

80 As hereinbefore stated, the door 2 is mounted to tilt or rock and to effect this result, the lower corner is made rounding, as shown most clearly in Fig. 1. A metal bar 85 is secured to the rounding corner of the door and is adapted to sustain the wear. A companion bar is secured to the strip 10 and acts jointly with the bar applied to the rounding corner of the door to sustain the wear. As shown most clearly in Figs. 1 and 3, the 90 metal bar 12 secured to the rounding corner of the door is curved and provided upon its outer side with teeth 13. The extremities of the toothed curved bar 12 are provided with long teeth 14 which constitutes stops to 95 limit the movement of the door. As shown in Figs. 1, 2 and 3, the bar 12 is in the plane of the door.

100 The metal bar 15 applied to the strip 10 is straight and is toothed upon its upper side to mesh with the teeth 13 of the bar 12 and is provided at its ends with long teeth 16 to coact with the teeth 14 at the ends of the bar 12. By having the curved bar 12 and the straight bar 15 formed with intermeshing teeth, the door is caused to move uniformly when opening and closing, so that the terminal teeth 14 and 16 will coact in either extreme position of the door, as indicated in Fig. 1.

Having thus fully described my invention, what I claim as new and desire to secure by Letters Patent is:—

In combination with a car body having an opening, a door mounted upon said body and provided with a rounded lower corner having a curved rack member terminating in laterally extending fingers at the respective ends thereof for constituting a means for 10 limiting the swinging movement of the door, a flat rack bar adapted to mesh with the curved rack bar carried by the door, a detachable strap lock engaging the upper end of the door for holding the same in a closed

position, spaced spring members engaging 15 the door when in the closed position for holding the same firmly upon the car, and a spring retaining member carried by said car and overhanging the lower curved corner of the door for firmly retaining the rack carried by the door in engagement with the rack carried by the car. 20

In testimony whereof I affix my signature in presence of two witnesses.

STEPHEN H. LOVETT.
